[57] CLAIM

The ornamental design for a telephone handset, as shown and described.

DESCRIPTION

FIG. 1 is a front elevation of the telephone handset of my new ornamental design;
 FIG. 2 is a rear elevation thereof;
 FIG. 3 is a left side elevation thereof;
 FIG. 4 is a right side elevation thereof;
 FIG. 5 is a top plan view thereof;
 FIG. 6 is a bottom plan view thereof;
 FIG. 7 is a front, left bottom perspective view thereof;
 FIG. 8 is a top, left rear perspective view thereof;
 FIG. 9 is a front elevation showing the telephone handset of my new ornamental design, with clip;
 FIG. 10 is a rear elevation thereof;
 FIG. 11 is a left side elevation thereof;
 FIG. 12 is a right side elevation thereof;
 FIG. 13 is a top plan view thereof;
 FIG. 14 is a bottom plan view thereof;
 FIG. 15 is an elevation of the clip shown removed from the handset for purposes of illustration only;
 FIG. 16 is a front, left bottom perspective view of the handset according to FIG. 9; and,
 FIG. 17 is a left, rear top perspective view thereof.
 The items shown in broken lines are shown for illustrative purposes only and do not form part of the claimed design. Any portions of the article hidden behind broken line disclosure are not a part of the claimed design.
